CLAIM

The ornamental design for a desktop receptacle, as shown and described.

DESCRIPTION

FIG. 1 is a perspective view of a first embodiment of a desktop receptacle showing our new design;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is another side view thereof opposite the side shown in FIG. 6;

FIG. 8 is a perspective view of a second embodiment of a desktop receptacle showing our design; and,

FIG. 9 is a front view of the desktop receptacle shown in FIG. 8.

The broken lines in the drawings are for the purpose of illustrating portions of the desktop receptacle that form no part of the claimed design.
